UNITED STATES PATENT OFFICE

2,357,868

APPARATUS FOR DISTRIBUTING SOLID MATERIAL

Arthur C. Beardslee, Arcade, N. Y., assignor to
The Borden Company, New York, N. Y., a corporation of New Jersey

Application April 8, 1941, Serial No. 387,433

10 Claims. (Cl. 34—112)

This application is a continuation-in-part of my application Serial No. 192,486, filed February 25, 1938, which matured into Patent 2,336,461, issued December 14, 1943.

The invention relates to a drying process and apparatus, and more particularly to means for distributing finely divided solids over the surface of a film of partly dry material undergoing drying.

In the usual process of roller or drum drying, carried out either at atmospheric pressure or under a partial vacuum, the material to be dried in the form of a concentrated liquid is fed to the surface of one or more heated rolls which are rotated slowly. This film of material on the roll ordinarily becomes dry before one revolution of the roll is completed and is scraped from the roll in dried form by a "doctor blade." Many materials, however, are very difficult to dry by this economical method because after they are partially dehydrated, they become sticky and the dehydration is arrested by the physical character of the partly dried film that is formed. It is very difficult to scrape such materials from the roll and when they are removed, they frequently cool to form a hard rock-like mass. This is particularly true with respect to such materials as whey and other materials containing a high proportion of melassigenic salts.

Various proteinaceous materials present a similar difficulty in drying, one good example of which is the wash water obtained from the preparation of fish products and known as "stick-water" or "fish stick." This wash water when concentrated is high in colloidal proteins that offer considerable resistance to drying on a heated drum or roll.

In my copending application Serial No. 192,486, a method of overcoming the difficulty of drying such materials on a drum or roll is described and claimed. This method involves the application of finely divided solids of the same or a different composition to a partially dried film of material while it is being dried on the drum or roll. In the case of materials being dried that contain quantities of melassigenic salts, I believe the effect of adding the finely divided solids is to initiate crystallization or serve as a "seeding" material and thus change the physical character of the sticky film sufficiently to enable the balance of the moisture to be driven off.

In the case of the protein materials, it is likely that another phenomenon is responsible for the improved drying effect obtained. In any event, it has been found that materials normally difficult

to dry and normally producing very hygroscopic products, can be satisfactorily dried by the usual drum or roller method using this simple expedient of distributing finely divided solids on top of the partly dry film of material on the roll surface.

An object of this invention is to provide apparatus peculiarly suited and adapted for distributing and depositing such finely divided solids.

A further object of this invention is to provide apparatus capable of feeding such finely divided solids uniformly over the surface of a roll in spite of steam and warm air currents rising from the heated roll.

Other objects will be explained and will be apparent from a description of two embodiments of this invention illustrated in the accompanying drawings, in which:

Figure 1 is a partially diagrammatic end elevation showing a preferred form of solids distributor arranged for operation over the surfaces of two drums of a double roll dryer.

Figure 2 is a vertical longitudinal sectional view through approximately the center of the solids distributing apparatus shown in Fig. 1.

Figure 3 is a vertical sectional view of the apparatus, taken on the line 3—3 of Fig. 2.

Figure 4 is a vertical sectional view showing an operating cam for the apparatus, and taken on the line 4—4 of Fig. 2.

Figure 5 is a fractional view of the apparatus, partly in section, taken on the line 5—5 of Fig. 2.

Figure 6 is a vertical longitudinal sectional view through approximately the center of a modified form of distributing and depositing apparatus.

Figure 7 is a vertical sectional view of this modified apparatus, taken on the line 7—7 of Fig. 6.

Figure 8 is a fractional side elevation of a modification of the apparatus shown in Figs. 1 to 5.

Figure 9 is a vertical sectional view on the line 9—9 of Fig. 8.

Figure 1 illustrates one form of the apparatus as applied to a double roll dryer in which the rolls or drums 10 and 11 are located side by side and rotated simultaneously in opposite directions. With such a construction, it is convenient to supply the liquid to be dried to the roll surfaces just below the "pinch" thereof. As these roll surfaces move upwardly and away from each other carrying the material being dried, the finely divided solids carried in the tube 12 are distributed over the surfaces of this material on the

rolls 10 and 11, falling by gravity out through the distributing chamber 13.

The tube 12 carrying the finely divided solids to be distributed may be conveniently supported in a fixed position above the roll surfaces by means of the fixed block 14 at one end and the bracket 15 at the other end. The ends of tube 12 may be closed by the bearing blocks 16 and 17. A suitable screw conveyor 18, arranged for rotation within the tube 12 may have its shaft journaled at one end in the block 14 and bearing block 16, and in the bracket 15 and bearing block 17 at the other end. Rotation of the screw conveyor may be obtained from any suitable source of power (not shown) by means of the chain 19 and the sprocket wheel 20 keyed to one end of the conveyor shaft.

Solids to be distributed may be supplied to the tube 12 at one end thereof from a hopper or any other suitable source through the feed tube 21. Near the other end of tube 12 an outlet 22 for excess solids may be provided. The solids that are to be distributed fall out of the tube 12 through the longitudinal slot 23 in the bottom thereof.

Surrounding the tube 12 is a partially cylindrical casing 24 having an opening 25 in its bottom and being supported for rotation relative to the tube by the end portions 26 which bear directly on the outer surfaces of the tube 12 so that the remainder of the casing 24 is spaced therefrom. Attached to the sides of the casing 24 on each side of the opening 25 at the bottom thereof are the laminated walls 27 and 28 of the distributing chamber 13. These walls may be composed of two sheets of metal with a suitable layer of insulating material therebetween. At their upper edges, the walls 27 and 28 may be welded, riveted or otherwise secured to the casing 24, and converge downwardly therefrom so that a slot is formed between the flanges 30 and 31 at their lowermost edges. The ends of the distributing chamber 13 may be closed by end walls 32 and 33 suitably attached to the side walls 27 and 28. A pivotally suspended distributing chamber is thus provided, adapted to swing back and forth around the tube 12, and so arranged as to receive all of the solids falling through the slot 23 in the tube 12.

To assist in the operation of the device and prevent steam rising from the rolls from clogging this solids distributor, warm air or unheated air under a slight pressure may be introduced into the distributing chamber 13 through a flexible hose or pipe 34 attached to end wall 32.

Suitable provision may be made for swinging the distributor chamber 13 back and forth. For example, the rod 35, reciprocated by a crank or any other suitable driving means (not shown), may have one end pivotally attached, as at 36, to the bearing block 37 fixed to the end wall 33.

An agitator mechanism for the slot between flanges 30 and 31 may also be provided consisting of several bands 38, three of which are illustrated in the drawings, surrounding the tube 12 in sliding engagement. The lower ends of these annular bands 38 may be pivotally connected by means of the rivets 39 to swinging links 40, and the lower ends of the links 40 are pivotally connected by means of the bolts 41 to an agitator bar 42.

This agitator bar is preferably provided with a serrated lower edge 43 which projects through the slot between the flanges 30 and 31. The

agitator bar 42 may be reciprocated longitudinally through an arcuate path by means of the operating arm 44 pivotally connected as at 45 to one of the vertical links 40. The operating bar 44 projects through an opening in the end wall 33 and a suitable small opening in the bearing block 37, and carries on its outer end a roller follower 46.

Clamped to the tube 12 at one end of the distributing chamber 13, and preferably outside thereof, is a fixed bracket 47 provided with a curved and inclined groove or track 48 in which the roller follower 46 is adapted to travel. Groove 48 is curved about tube 12 as a center and is inclined with respect to a plane passed at right angles through tube 12 in order to impart a longitudinally reciprocating motion to the arm 44 as chamber 13 swings back and forth.

In the operation of this device, the liquid to be dried is fed to the heated roll surfaces 10 and 11, and is carried on these surfaces upwardly and outwardly away from each other. Finely divided solids to be deposited on this film of material being dried are fed from a hopper or other suitable source by gravity through the inlet 21 to the screw conveyor 18 in tube 12. This screw conveyor is rotated in a clockwise direction, as viewed in Figures 1 and 3, to advance the solids along the tube 12 toward the exit 22. Finely divided solids suitable for distribution fall through the slot 23 into distributor chamber 13. The solids that are too large and any excess solids are moved along through tube 12 until they are dropped out through the exit 22 where they may be collected.

Reciprocation of the rod 35 swings the distributor chamber 13 back and forth pendulum fashion through an arcuate path, indicated by the curved line 49, above the surfaces of the rolls 10 and 11. As the distributor chamber 13 swings back and forth, the roller follower 46 reciprocating in the groove 48 causes the operating rod 44, links 40 and agitator bar 42 to swing back and forth through an arcuate path in a direction longitudinally of the distributor chamber 13. The longitudinal reciprocation together with some vertical reciprocation of the agitator bar 42 keeps the slot between flanges 30 and 31 open, preventing any clogging thereof and ensures uniform and continuous distribution of solids.

Air heated or unheated supplied to the distributor 13 through the hose 34 prevents steam from the rolls from condensing inside the distributor 13 and clogging the apparatus.

A somewhat simpler form of distributing and depositing apparatus is illustrated in Figs. 6 and 7 and may consist of a feed hopper 50 located above the surfaces of the rolls 10 and 11 in place of the tube 12 and distributor chamber 13 shown in Fig. 1. This feed hopper 50 may be conveniently constructed with inclined side walls 51, 52 connected near their lower portions by an arcuate section 53 provided with a longitudinally extending slot 54 in its lowermost portion. The ends of the hopper may be closed by suitable end walls 55.

This hopper, which may be open at its top or covered, is provided with a shaft 56 rotatably mounted in suitable bearings 57 attached to the end walls 55. Inside the hopper, shaft 56 is provided with a helical screw conveyor 58 which is disposed generally concentric with the lower arcuate portion 53 of the hopper. One end of the shaft 56 outside of the hopper 50 may be pro-

vided with a sprocket 59 driven by means of a chain 60 from an electric motor 61.

A reciprocating cleaning member 62 for the slot 54 may be provided with a pin section 63 projecting downwardly through the slot 54 and with a collar and head portion 64 adapted to slide along the upper surface of the walls of slot 54. A groove may be formed in the head portion 64 of the cleaning member 62 in which the edge of the helical conveyor 58 is adapted to slide. The cleaning member 62 is thus moved along the slot 54 by means of the conveyor 58 in one direction or the other depending upon the direction of rotation of conveyor 58. Suitable reversing switches 65 and 66 mounted at each end of the slot 54 may be connected to the motor 61 to reverse the motor each time the cleaning member 62 strikes one of the switches.

It will thus be seen that the conveyor screw 58 agitates finely divided material placed in the hopper 50 so that sufficient quantities are allowed to drop through the slot 54. The cleaning member 62 reciprocates back and forth through this slot, preventing any clogging thereof by reason of the moist air and steam rising from the drying rolls. If desired, the hopper 50 may be closed in a manner similar to the distributor 13 and provided with warm air or unheated air under pressure to prevent any steam from getting into the hopper 50 through the slot 54.

Suitable means may be provided, if desired, for varying the width of the slot in the solids distributing apparatus to control the rate of flow of the solids therethrough. One form of adjusting mechanism for this purpose is illustrated in Figs. 8 and 9 as applied to the embodiment of my invention shown in Figs. 1-5.

In this modification, the tube 70 carrying the screw conveyor 18 is fixed to the distributing chamber 13 and rotates therewith about its central longitudinal axis as the distributing chamber is rocked back and forth. The mechanism for rocking the distributor chamber, and for operating the agitator bar can be the same as described above, except that a suitable fixed support is provided for the bracket 41 instead of clamping this bracket to the tube 70.

The tube 70 has a longitudinal slot along its lower surface between the sharpened edges 71 and 72. A number of relatively narrow spring clips 73 are fixed to the tube 70 on one side of the slot and extend across the slot.

Mounted on the outside of the apparatus are a suitable number of bearing brackets 14 rotatably supporting the shaft 75. A number of links 76 are fixed to this shaft at intervals opposite the spring clips 73, and are pivotally connected at their lower ends to the wedges 77. These wedges 77 extend through openings 78 in the wall of chamber 13 into positions between the slot edge 71 and the spring clips 73.

Rotation of the shaft 75 may be effected by means of the hand operated lever 79 that may be provided with a slotted extension sliding over the stud 80 in order to clamp the lever in any given position by tightening the screw 81.

The slot in the bottom of tube 70 may thus be widened to increase the flow of solids therethrough by rotating the shaft 75 in a counter-clockwise direction as viewed in Fig. 9. This causes the links 76 to swing in an arc towards the chamber 13 which moves the wedges 77 into a canted position with the points of the wedges engaging the pockets between the spring clips 73 and the edge 72. Pressure of the wedges 77

on these pockets forces the edges 71 and 72 farther apart to form a wider slot for the passage of solids.

When this pressure of the wedges 77 is released, the natural resiliency of the tube 70 tends to move the edges 71 and 72 towards each other, thus narrowing the slot again.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. Apparatus for depositing finely divided solids comprising a container for said solids having an elongated opening in the lower portion thereof, means for supplying a gas under low pressure to the inside of said container for passage out through said opening, movable means projecting through said opening for preventing clogging thereof and ensuring a flow of said solids through said opening by gravity, and means for reciprocating said movable means back and forth in said opening.

2. Apparatus for distributing finely divided solids over a surface comprising a distributing chamber with a longitudinal discharge opening in its lower portion mounted for pivotal movement about a longitudinal axis near the upper portion thereof, means for swinging said chamber back and forth about said axis, means operating in said opening to prevent clogging thereof, and means actuated by the swinging of said chamber for reciprocating said last named means in a direction longitudinally of said chamber and opening.

3. Apparatus for distributing finely divided solids over a surface comprising a container for solids having a discharge opening therein, a pivotally suspended distributor chamber arranged to receive solids from said opening, an elongated solids distributing slot in the lower portion of said chamber, and means for swinging said chamber back and forth in a direction transverse of said slot to disperse the solids discharged therefrom.

4. Apparatus for distributing finely divided solids over a surface comprising a container for solids having a discharge opening therein, a pivotally suspended distributor chamber arranged to receive solids from said opening, a solids distributing slot in the lower portion of said chamber, means for swinging said chamber back and forth to disperse solids discharged from said slot, and agitating means projecting into the slot for maintaining a steady passage of solids therethrough.

5. Apparatus for distributing finely divided solids over a surface comprising a container for solids having a discharge opening therein, a pivotally suspended distributor chamber arranged to receive solids from said opening, a solids distributing slot in the lower portion of said chamber, means for swinging said chamber back and forth to disperse solids discharged from said slot, and an agitator bar movable longitudinally of said slot for preventing clogging thereof.

6. Apparatus for distributing finely divided solids over a surface, a tubular member having a longitudinal opening in the bottom thereof, conveyor means in said member for moving solids along over said opening, a distributing chamber pivotally suspended from said member to receive

solids therefrom, means forming a slot in the lower portion of said chamber, means for swinging said chamber back and forth, and means movable in said slot for preventing clogging thereof.

7. Apparatus for distributing finely divided solids over the surface of partially dried material on a drum dryer which comprises a chamber supported above such drum in a position to deposit finely divided solids thereon, said chamber having a long narrow opening in the bottom thereof extending in the direction of the drum, means for supplying air under a low pressure to the interior of said chamber, means projecting through said opening to prevent clogging thereof, and means for moving said projecting means back and forth longitudinally of said opening.

8. In apparatus of the character described, a hopper for finely divided solid material, a slot in a lower portion of said hopper for discharging said material, a screw conveyor in said hopper adjacent said slot, power means for driving said conveyor, a cleaning member adapted to slide in said slot upon actuation by said conveyor, and means at the ends of said slot operated by said

member for reversing the direction of driving of said power means.

9. Apparatus for distributing finely divided solids over the surface of partially dried material on a roll comprising a container for solids located above such roll and having an elongated slot in the bottom thereof, a screw conveyor in said container adjacent said slot, a cleaning pin projecting through said slot having a sliding contact with said conveyor, and means for rotating said conveyor to agitate solids in the container and move said pin along said slot.

10. Apparatus for distributing finely divided solids over a surface comprising means forming an elongated chamber with a long narrow opening in the bottom thereof, means suspending said chamber for reciprocating movement in a direction transverse to the direction of said opening, means extending through said opening and movable back and forth therein for preventing clogging of the opening, and means for varying the rate of flow of solids through said opening.

ARTHUR C. BEARDSLEE.
